CANE MILL

Francis Hegenbarth, Wilkes-Barre, Pa., assignor
to Vulcan Iron Works, Wilkes-Barre, Pa., a cor-
poration of Pennsylvania

Application January 3, 1946, Serial No. 638,725

4 Claims. (Cl. 308—9)

1

The present invention relates to improvements in cane mills, and has more particular reference to an improved adaptable bearing construction for the top roll journals of such mill.

Modern cane mills consist of two side rolls in fixed location and one top roll movable in top bearings which are slidably mounted in the mill housing. Such arrangement permits the lift of the top roll whenever irregular batches of cane enter between the mill rolls where the cane is crushed and the juice extracted by the pressure between the rolls. A hydraulic ram provides heavy load pressure upon both end journals of the top roll shaft, but permits vertical floating of the top roll as required for the passage through the rolls of the cane when the feed is irregular.

An object of the present invention is to modify the flat planar meeting surfaces between the standard pressure plate and the upper top roll bearing to provide mutual large spherical bearing surfaces to enable the top roll bearing to rotate relatively to the pressure plate incident to the axial tilting of the top roll to permit and facilitate such tilting movements of the top roll without affecting or communicating a like movement to the pressure plate and the ram as it is highly desirable that such pressure plate and ram partake only of a vertical rectilinear movement.

Another object of the invention is to further promote and facilitate tilting movements of the upper roll, its journals and bearings to compensate for irregularity in the feed by cutting back the bearing flanges to provide adequate clearance between the same and the sides of the pressure plate, thus permitting the side bearing flanges to participate in the tilting movement referred to without disturbing or having any lateral tendency to displace the pressure plate which is thus left undisturbed in its true vertical and aligned position with respect to the ram.

A further object of the present invention is to additionally promote and facilitate correct and true bearing action in permitting the tilting movements of the upper roll referred to by providing for adequate and complete lubricant between the large mutually concave and convex spherical surfaces on which the turning moments

of the top roll bearing are achieved in an instantaneously responsive manner substantially free from wear.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a side elevation of a conventional type of cane mill, with parts broken away and parts shown in section, illustrating the improved bearing and pressure plate construction.

15 Figure 2 is a vertical section taken through the central portions of the hydraulic ram and bearings substantially at right angles to Figure 1.

Figure 3 is a view similar to the right hand portion of Figure 2 illustrating the action on axial 20 tilting of the top roll.

Figure 4 is a detached view of the coacting parts of the top bearing and pressure plate with the pressure plate shown in section and the top bearing shown in elevation and partially broken away and

Figure 5 is a top plan view of the modified construction of the top bearing and with the journal of the top roll partly broken away.

Referring more particularly to the drawings
30 10 designates generally a mill housing of a standard construction in which is installed the hydraulic top caps 11 with vertically reciprocating hydraulic rams 12 which develop downward thrust upon pressure plates 13.

35 The top roll bearings 14 are slideable in the mill housing and receive downward pressure from the pressure plate 13. At 15 is indicated the top roll journal and at 16 the top roll.

40 This top roll 16 cooperates in a well known manner with a side or cane roll having a journal 17 and with a discharge or bagasse roll the journal of which is seen at 18. The standard ram 12 is made with a lower convex surface 19
45 which fits into a concave upper surface of the pressure plate 13.

The standard pressure plate has its lower or bottom surface in a horizontal plane and appears as a flat face which rests upon an equally flat upper face of the top roll bearing 14. In

other words these faces meet in a substantially horizontal plane throughout.

According to the present invention these co-planar surfaces are modified into a large concave spherical bearing surface 21 at the lower end or bottom of the pressure plate 13 and a complementary large convex spherical bearing surface 22 at the upper end or top of the top roll bearing 14. These surfaces 21 and 22 have great or large diameter as compared with the surfaces 19, 20 at the upper reduced portion of the pressure plate 13. Oil or grease grooves 23 may be made in either surface 21 or 22 of any desired pattern for the purpose of lubricating the entire areas of the contacting surfaces 21, 22. In this instance there is shown by way of example a number of curved radiating shallow grooves 23 in the upper convex surface 22 all of which communicate with a central lubricant supply duct 23 in the pressure plate 13 which has communication in any desired or well known manner with a source of appropriate lubricant.

Referring more particularly to Figures 3 and 4 the bearing flanges 25 are shown as being cut back as indicated at 26, such cut back taking place preferably along inclined lines. These cut back portions are made upon the inner surfaces of the bearing flanges 25 and converge upwardly from wide bases toward the outer vertical walls of the flanges 25. This arrangement leaves undisturbed the lower original thicknesses of the side flanges 25 in order that they may adequately fit the journal 15 and the sides of the top roll bearing 14 without any play; but the cut back increases upwardly to provide adequate clearance for the flanges when the top roll 16 is axially tilted as indicated in Figure 3. Thus the inner sides of the bearing flanges 25 avoids striking the sides of the pressure plate 13 which would not only interfere with the free tilting movement of the top roll but would also tend to displace or undesirably rotate the pressure plate 13.

The top roll bearings 14 are customarily of bronze and the standard construction of pressure plate with its flat base surface bears against a flat top surface of the top roll bearing 14. The hydraulic ram 12 presses against the top of the pressure plate 13 in a spherical depression 19, 20. It will be noted that this surface 19, 20 is of necessity comparatively small. With mills using up to 600 tons load on top rolls or 600,000 lbs. on each ram, the ram being about nine inches in diameter the corresponding surface pressure at the spherical lower end 19, 20 of the ram will be approximately 9400 lbs. per square inch. It is obvious that with such pressure upon the spherical ram end a lubricating film on that surface cannot be maintained, and if any alignment there occurs it could only take place under excessive unit pressure and after overcoming the binding effect thereon.

In accordance with the present invention and with the use of the spherical surfaces 21, 22 at the lower end of the pressure plate 13, the standard top bearing 14 possesses dimensions which will permit the diameter of the spherical surfaces 21, 22 to be large enough to reduce the unit pressure there to from 1600 to 1800 lbs. per square inch; which will permit the use of effective films of lubricants between these parts, and result in a free movement over the spherical surface. The fact that the top bearing 14 is of bronze and the pressure plate 13 of steel will contribute to the reduction of friction over the large spherical joint 21, 22. The grooves 23 provide for the

effective distribution of lubricant over the spherical surfaces 21, 22, the lubricant being conventionally introduced through the side of the pressure plate by means of the duct 24.

5 The upper surface of the improved pressure plate 13 is provided in the usual way with the spherical indentation 20 to serve as a seat for the lower spherical end 19 of the ram 12 but these surfaces 19, 20 in no way facilitate or promote any lateral or rotary movement of the pressure plate 13 with reference to the ram 12. The pressure plate at all times will remain in a true horizontal position. All of the movement of the top bearing 14 is performed over the large spherical surfaces 21, 22 between the top bearing 14 and the pressure plate 13 and therefore all such tilting movements will be confined to the top roller bearing 14 and the bearing flanges 25 without being in any way communicated to the pressure plate 13.

Figure 2 shows the top roll 16 in normal or horizontal position.

Figure 3 indicates the same roll 16 as lifted up at one end, for instance at such times when irregular cane feed is passing through the mill. At such times a tilting pressure is executed against the bearing 14 by the shaft journal 15. If the bearing 14 is not permitted to assume the position of the journal then the shaft of the top roll must assume an inclined position within the bearing 14. This causes the journal 15 to bear on one end of its length only. Or, with the small spherical ram surface available with the standard mill construction a violent jarring alignment may occur, not at all of the free moving nature which is needed to permit instantaneous reaction upon the hydraulic ram and pressure cylinder, so that the rise of the top roll may occur without lag and in perfect synchronism with excess loads from heavy irregular feed of cane between the rolls.

It will be appreciated that the larger spherical couple 21, 22 avoids this advantage with the prior flat surfaced construction.

45 It is obvious that various changes and modifications may be made in the details of construction and design of the above specifically described embodiment of this invention without departing from the spirit thereof, such changes and modifications being restricted only by the scope of the following claims.

What is claimed is:

1. In a cane mill having a pressure roll with a journal, a bearing fitted to the journal and mounted for sliding movement in the mill, a pressure plate bearing against said bearing, a hydraulic press having a ram bearing against said pressure plate, said ram and pressure plate having mutual contacting spherical surfaces therebetween of a comparatively narrow spherical section, said pressure plate and bearing having contacting mutually spherical surfaces therebetween of a comparatively larger spherical section.

2. A cane mill as claimed in claim 1 characterized by the fact that the upper portion of the pressure plate is narrower than the lower portion.

3. In a cane mill, a pressure roll having a journal, a bearing fitted to said journal and having a large part-spherical upper end, flanges on the said bearing projecting outwardly beyond the bearing, the inner walls of said flanges being cut back along tapering lines which diverge outwardly toward the outer side walls of the flanges, 70 a pressure plate having a spherical concavity

fitted to the convexity of the bearing to enable the bearing to rotate with reference to the pressure plate without disturbing the longitudinal alignment of the pressure plate and means for imposing pressure on said pressure plate, said inner walls of said flanges being cut back to avoid striking the sides of the pressure plate in the endwise tilting rotational movement of the bearing.

4. A cane mill having a roll subject to axial tilting and a bearing fitted tightly to the journal of the roll and subject to pressure from a pressure device through a pressure plate engaging the bearing, characterized by the fact that the pressure plate and bearing have complementary large spherical surfaces and said bearing having cut back flanges, said complementary spherical surfaces being provided for enabling the bearing

to rotate relatively to the pressure plate without disturbing the vertical alignment of the latter and in so doing to follow the axial tilting of the journal of the roll, said bearing flanges being cut back to avoid striking the sides of the pressure plate in the endwise tilting rotational movement of the bearing.
